CLIFFORD JAMES ALPAUGH, OF TRENTON, NEW JERSEY, ASSIGNOR TO TRENTON ELECTRIC AND CONDUIT COMPANY, OF TRENTON, NEW JERSEY, A CORPORATION OF NEW JERSEY.

SWIVEL ATTACHMENT-PLUG.

1,164,249.

Specification of Letters Patent. Patented Dec. 14, 1915.

Application filed March 22, 1915. Serial No. 16,068.

To all whom it may concern:

Be it known that I, CLIFFORD J. ALPAUGH, a citizen of the United States of America, and residing at Trenton, in the county of 5 Mercer and State of New Jersey, have invented certain new and useful Improvements in Swivel Attachment-Plugs, of which the following is a specification, such as will enable those skilled in the art to which it 10 appertains to make and use the same.

My invention relates to attachment plugs for flexible electrical conductors, and the main object thereof is to provide such plugs of swivel form whereby they may be screwed 15 into a socket, lamp or other device, without twisting or disturbing said conductors in the least. I am aware that several different types of such plugs have been made and marketed, but my plug differs from any known to me 20 because of the great simplicity thereof, inasmuch as it consists of but two elements readily connected to and disconnected from each other without the use of a tool. Another distinction resides in the fact that these two 25 elements are only held together by friction which, however, permits free revolution of one element upon the other. A further distinction is that, when the threaded element is screwed into a socket, this operation locks 30 said elements against any possibility of separation, despite the fact that the conductor carrying element is merely telescoped into the threaded element, and readily separated therefrom. And further distinctions exist in 35 the ready accessibility of the conductor binding screws, whereby the conductors may be connected with the plug in a neat and workmanlike manner, and in the fact that the said conductor connections are entirely concealed 40 and fully protected, despite the fact that the plug consists of but two elements.

My invention is fully described in the following specification, of which the following 45 drawings form a part, in which like reference characters refer to like parts in each of the views, and in which:—

Figure 1 is a side elevation of a swivel plug constructed in accordance with my present invention; Fig. 2 is a section taken on 50 the line 2—2 of Fig. 1; and Fig. 3 is a section taken on the line 3—3 of Fig. 2.

In the drawings forming a part of this application I have shown a present preferred

form of embodiment of my invention, comprising a conductor carrying element 4 and a 55 screw-threaded element 5, the former of which has the two conductors 6 and 7 connected therewith, and the latter of which carries the screw-threaded shell 8 of the conventional form and which, as will be understood, is adapted to be screwed into a similarly threaded socket, such as a conventional lamp socket.

The element 4 consists of a head 9 having a dependent, cylindrical, member 10 of less 65 diameter than said head, the member 10 being recessed at 11 and 12 at diametrically opposite sides to provide seats for plates 13 and 14, respectively, provided with binding screws 15 and 16, respectively, for the respective conductors 6 and 7, and it will be noted that said conductors and screws are contained entirely within the periphery of the dependent member 10. The plate 13 is extended beneath the element 4 in order to 75 provide a connection with a screw 17 passed inwardly from the forward end of said element and serving as the central contact of the plug, a washer 18 being employed to reinforce said screw at its head. 80

The plate 14 is bent at right angles to form a contact 19 adapted to bear on the screw-threaded shell 8 when the elements are in operative connection, as clearly shown in Fig. 2, and I may employ a screw 20 to 85 maintain the same in position, said shell constituting, as in conventional plugs, the other socket contact of the plug.

The element 5 is provided with a larger bore of the approximate diameter of the 90 dependent member 10, whereby, when the elements are joined, a frictional engagement results therebetween of sufficient strength to prevent the accidental separation of the elements, but not so strong as to prevent 95 rotary movement of the element 5 with respect to the element 4; said element 5 is also provided with a smaller bore for the passage of the conductors 6 and 7, as is clearly illustrated in Fig. 2, said conductors 100 being shown as sheathed in the drawings, and I will, although not shown, prefer to tape said conductors together between the sheath thereof and the element 4 to maintain the same in relative positions. Both 105 the elements 4 and 5 are made of insulat-

- ing material, the former being made of porcelain if desired, and the latter of what is technically known as composition, being preferably molded into the screw-threaded shell 8; if of these materials, it will be observed that the relatively soft composition adapts itself to the inequalities of the relatively hard and brittle porcelain, as it would be practically impossible to insure the snug fit of the dependent member 10 within the element 5 if both elements were made of porcelain because of the lack of uniformity of size and accuracy of porcelain objects after being baked.
- 15 While the above are the materials of which I prefer at present to make the two elements, obviously I do not confine myself to any specific materials, as many substitutes for the above may be employed and 20 be just as efficient, but the above materials result in a very inexpensive plug and serve the purpose fully as well as more costly materials.

It will be seen, by reference to the dotted lines in Fig. 1, that the elements may be manually separated, the element 5 being drawn off the element 4 and backwardly on the conductors, thus giving easy and instant access to the binding screws 15 and 16 for 25 conductor connection or disconnection, and it will also be seen that, when the elements are in operative connection, the conductor connections with the element 4 are entirely concealed and fully protected against short-circuiting. Further, when the elements are 30 in operative connection and the element 5 is screwed into a socket, no separation of the elements can possibly occur, the element 5

constituting the locking element when connected with the socket.

My invention is extremely simple, though well adapted to the purpose for which it is intended, and the conductors are not affected by connecting the plug with a socket.

With a reservation to myself of all such changes as may come within the scope of the following claim, what I claim as new, and desire to secure by Letters Patent, is:—

An attachment plug comprising a male member and a female member in rotary and frictional engagement, said male member being provided with a shoulder for limiting its inward movement and with grooves on opposite sides thereof, a conductive screw passed through the length of said male member, a conductive plate held by said screw and bent to rest in one of said grooves, a binding screw on said plate; a supplemental conductive plate held in the other groove and bent outwardly to project over the outer end of said female member, a binding screw for said supplemental plate, and a screw threaded sleeve on said female member inwardly flanged over the outer end thereof to provide a conductive bearing surface for the bent portion of the supplemental conductive plate in the rotation of one member with respect to the other.

In testimony that I claim the foregoing as my invention I have signed my name in presence of the subscribing witnesses this 15th day of March 1915.

CLIFFORD JAMES ALPAUGH.
